(74) Attorney, Agent, or Firm — Garlick & Markison;
Bruce E. Garlick(57) **CLAIM**

The ornamental design for a vehicle wheel face, substantially as shown and described.

DESCRIPTION

FIG. 1 is a front view of a vehicle wheel face, showing our new design.

FIG. 2 is a side view thereof; and,

FIG. 3 is a perspective view thereof.

The portions of the vehicle wheel shown in a lighter grey scale represent environmental subject matter and form no part of the claimed design.
